UNITED STATES PATENT OFFICE.

JOHN LAWRENCE, OF COLUMBUS, OHIO.

ACETYLENE-GAS GENERATOR.

SPECIFICATION forming part of Letters Patent No. 655,446, dated August 7, 1900.

Application filed October 5, 1899. Serial No. 732,611. (No model.)

To all whom it may concern:

Be it known that I, JOHN LAWRENCE, a citizen of the United States, residing at Columbus, in the county of Franklin and State of Ohio, have invented certain new and useful Improvements in Acetylene-Gas Generators; and I do declare the following to be a full, clear, and exact description of the invention, such as will enable others skilled in the art to 10 which it appertains to make and use the same.

The invention relates to improvements in acetylene-gas generators; and the object of the invention is to simplify and improve the construction and increase the efficiency of the 15 machine.

To this end the invention consists in certain features of construction and combination of parts, which will be hereinafter fully described, and particularly pointed out in the 20 claim.

In the accompanying drawings, Figure 1 is a vertical section of my improved acetylene-gas generator. Fig. 2 is a similar view taken at right angles to the section shown in Fig. 1. Fig. 3 is a detail perspective view of the carbid-basket removed from the bell. Fig. 4 is a detail view of the mouth of the bell, with a portion of the wall broken away to show the condenser-chamber.

30 In the drawings the same reference characters indicate the same parts of the invention.

1 denotes the tank, and 2 the bell.

3 denotes a relief-pipe which forms a safety-valve in the event of the gas generating faster than it is consumed. The relief-pipe 3 is formed integral with the bell 2 and projects slightly through the top of the same, as shown in Figs. 1 and 2.

40 4 denotes the condenser-chamber fixed in the mouth of the bell; and it consists of horizontal plates 5 and 6, which form the parallel top and bottom of the condenser, the bell forming the curved wall thereof and the plate 45 7 forming the straight wall, the condenser-chamber being air-tight with the exception of the inlet-pipe 8, which extends above the carbid-basket 15, and the outlet-pipe 9, which extends up through the top of the bell and

50 terminates in a stop-cock 10. In practice the condenser-chamber may be made separate

and complete and afterward removably attached to or soldered in the bell.

12 represents a socket fixed to the inside of the bell, and 13 denotes a bracket removably secured in said socket. The upper end of the bracket terminates in a horizontal arm 14, to which the carbid-basket 15 is fixed.

The operation of the device is entirely automatic and simple. The carbid-basket is first 60 charged and then inserted in the bell, which is conveniently done by tilting the bell, so that the basket will enter the mouth of the bell between the straight wall of the condenser-chamber and the curved wall of the 65 bell and the bracket inserted in the socket in the bell.

The bottom of the carbid-basket is horizontal, and it will be noted that the horizontal arm of the bracket extends across the center of the bottom of the carbid-basket to act as a brace and prevent the basket sagging at the bottom.

In operation the tank 1 is partially filled with water about two-thirds full. The bell 75 2 is then placed within it, and the air-cock 10 is opened, permitting the air to escape from said bell 2 through the pipe 9, the stop-cock 10 being again closed after the air has escaped. The bell 2 will then sink by its own 80 weight until it is stopped by the stop-cock 10 engaging the top of the tank 1. A sufficient quantity of calcium carbid is then placed in the carbid-basket 15, which as soon as the calcium carbid comes in contact with the water generates the gas which fills the bell and is permitted to escape at the stop-cock 10 for consumption, except when the gas is being generated faster than it can be consumed, when the surplus gas escapes through the relief-pipe 3 into the open air.

It will of course be understood that various changes in the form, proportion, and the minor details of construction may be resorted to without departing from the principle or 95 sacrificing any of the advantages of this invention.

Having thus described the invention, what is claimed, and desired to be secured by Letters Patent of the United States, is—

In an acetylene-gas generator, the combination with the tank 1, of the bell 2 provided

with the outlet-pipe 3 supported in its top portion and projecting through the same; the condenser-chamber 4 at the bottom of said bell 2; the inlet-pipe 8 connected with said condenser-chamber and opening within the upper portion of said bell; the outlet-pipe 9 connected at its lower end with said condenser-chamber 4; extending through the top of bell 2, and provided with a stop-cock 10 near its upper end; the removable bracket 13 secured in the socket 12 fixed to the inside of

said bell 2 and terminating at its upper portion in the horizontal arm 14; and the carbide-basket 15 fixed to said horizontal arm 14; substantially as set forth.

15

In testimony whereof I have hereunto set my hand in presence of two subscribing witnesses.

JOHN LAWRENCE.
